UNITED STATES PATENT OFFICE.

LA MARCUS A. THOMPSON, OF NEW YORK, N. Y., ASSIGNOR TO THE L. A. THOMPSON SCENIC RAILWAY COMPANY, OF NEW YORK, N. Y., A CORPORATION OF NEW JERSEY.

SAFETY DEVICE FOR PLEASURE-RAILWAY CARS.

1,102,822.

Specification of Letters Patent.

Patented July 7, 1914.

Application filed April 10, 1914. Serial No. 831,068.

To all whom it may concern:

Be it known that I, LA MARCUS A. THOMPSON, a citizen of the United States, residing at New York, county of New York, and 5 State of New York, have invented a new and useful Improvement in Safety Devices for Pleasure-Railway Cars, of which the following is a full, clear, and exact description, reference being had to the accompanying 10 drawings, which form a part of this specification.

In pleasure railways, toboggan slides and racing coasters, accidents sometimes arise by reason of the occupants arising to a 15 standing position in their seats, from thoughtlessness, recklessness, or daring. When the car reaches a curve, a standing occupant is in grave danger of being thrown from the car by the operation of centrifugal 20 force. It is, therefore, advisable to provide means for locking the riders in their seats. This has been done by providing a safety device comprising a pivoted handle bar which may be swung forwardly to allow 25 riders to enter the car and assume their seats and then swing rearwardly to bring the bar into position in front of the trunks and above the legs of the riders. Means have been provided to secure the safety device in 30 locking position and also to release the same to allow the riders to enter and leave the car.

The object of my invention is to provide new and improved locking means accomplishing the results above set forth which 35 will have certain advantages over known means in respect to simplicity of construction and operation and unlikelihood of getting out of order and in respect to its possession of other advantages and functions, 40 all of which will be more fully understood by reference to the particular description in connection with the drawings, in which:

Figure 1 is a perspective view of the track, loading and unloading stations, and cams 45 for releasing safety device. Fig. 2 is a sectional perspective view of part of a car with safety devices applied thereto. Figs. 3 and 4 are side elevations, respectively in locked and unlocked position, of the safety device. 50 *a* is the loading station, *b* the unloading station, *c* the track, and *d* the car. The safety device is in the form of a yoke comprising the cross bar *e* and arms *f*, *f*, each of the latter being pivotally mounted between 55 vertically extending guide plates *g*, *g*, with-

in, and projecting from the rear wall of, a casing *h* secured to the car body.

Within the channel formed between the guide plates *g*, *g* slides a locking bar *i*. The upper end of the channel is closed by a cross-piece or stop *m*, while a cross-piece or stop *n* connects the lower ends of the guide plates and is adapted to limit the downward movement of the bar *i* by engaging a projection *j* on the bar. 60

The upper end of the bar *i* is widened to form a cam *k* which is widest at its top and tapers downward and thence extends abruptly inward to form a shoulder *l*. The pivoted end of the arm *f* is also enlarged to 70 form an upwardly and inwardly projecting cam *o*.

When the bar *i* is held in a raised position, the arm *f* is free to move forward and upward on its pivot, the high point of the cam *o* passing under the shoulder *l*. Or if the bar is lifted substantially above its lowest position, but not to its extreme upper position, the cam *o* will act upon cam *k* to raise the bar *i* to its extreme upper position and 75 allow the high point of the cam *o* to ride under the shoulder *l*. As the arm *f* is completing its movement into its extreme upper or forward position, the high point of the cam *o* moves slightly downward in an 80 inclined direction, allowing the spring cushion or spring *p*, between the upper end of bar *i* and the stop *m*, to move the bar *i* slightly downward, thus releasably holding the arm *f* in its upward or forward position, but permitting it to be depressed with the exercise 85 of moderate manual force. 90

When the yoke *e* *f* is swung downward and rearward into its locking position, the bar *i*, unless otherwise upheld, drops until 95 the projection *j* abuts against the stop *n*, placing the cam *k* in such position that it acts as a stop against the cam *o* to prevent the arm *f* from being swung upward and forward. 100

Each bar *i* extends downward beneath the car-body and is in alinement with cams *s*, *t*, arranged along the track. One pair of cams is provided at the loading station and another pair at the unloading station. 105

Let it be assumed that the car is traveling along the course and that the yoke *e* *f* has been swung into position to lock the occupants in their seats, and that each bar *i* has dropped so as to prevent the yoke *e* *f* 110

from swinging into its unlocking position. When the car has arrived near or at the unloading station, the lower ends of the bars *i* engage the cams *s*, which lift the bars *i* sufficiently high to allow the yoke *e f* to be swung into position to free the passengers. So long as the car remains at the unloading station, the yoke *e f* can be freely swung in either direction. In the travel of 10 the car from the loading station to the unloading station, the bars *i* pass beyond the cams *s*. If the yoke *e f* has been moved into its unlocking position, it remains in that position owing to the downward pressure 15 of the shoulder *l* against the cam *o*. If the yoke *e f* has been moved into its locking position, the bars *i* drop as soon as they pass beyond cam *s*, thereby locking the yoke in its locking position. When the car 20 reaches or nears the loading station, the lower ends of bars *i* engage cams *t*, which, like cams *s*, lift the bars *i* high enough to permit the return of the yoke *e f* into position to allow ready ingress to the cars. So 25 long as the car remains at the loading station, the yoke *e f* is freely movable from either position to the other. Before the car starts, the attendant swings the yoke *e f* into position to retain the passengers 30 in their seats and as soon as bars *i*, in the starting movement of the car, move beyond cams *t*, the bars drop and lock the yoke from being swung into its unloading position.

35 It will be observed that the entire mechanism comprises only two moving parts, the yoke *e f* and the locking bar *i*.

Having now fully described my invention, what I claim and desire to protect by Letters Patent is—

40 1. In a pleasure railway, the combination with the car, of a safety device movable thereon for locking the passengers to their seats, and a vertically extending locking bar 45 slidable in the direction of its length and adapted to be upheld by the safety device when the latter is in locking position and to slide down by gravity, as the safety device is moved into locking position, into 50 position to lock the safety device from returning.

55 2. In a pleasure railway, the combination with the car, of a movable safety device for locking the passengers in their seats including a pivoted arm having a cam, and a locking bar having a cam adapted, when the safety device is moved away from its locking position, to move in front of the cam on the arm and thereby lock the safety 60 device from being returned to its unlocking position.

3. In a pleasure railway, the combination with the car, of a movable safety device for locking the passengers in their seats including a pivoted arm having a cam, a slid-

able locking bar provided with a cam adapted, when the safety device is moved into locking position, to slide down with the bar and move in front of the cam on the arm to lock the safety device in such position, but adapted, when moved up, to recede from the car on the arm and thus free the safety device and permit it to be moved into unlocking position.

4. In a pleasure railway, the combination 75 with the car, of a movable safety device for locking the passengers in their seats including a pivoted arm, a locking bar slidable vertically and provided with a member having a cam face and a shoulder, said arm having a cam adapted, when the locking bar is raised to a determinate height, to engage said cam face in the movement of the safety device away from its locking position and thereby still further lift the locking bar and move under said shoulder, thereby holding the locking bar up.

5. In a pleasure railway, the combination 90 with the car, of a movable safety device for locking the passengers in their seats including a pivoted arm, a locking bar slidable vertically and provided with a member having a cam face and a shoulder, said arm having a cam adapted, when the locking bar is raised to a determinate height, to engage said cam face in the movement of the safety device away from its locking position and thereby still further lift the locking bar and move under said shoulder, thereby holding the locking bar up, and a spring 95 tending to move the locking bar down, whereby the safety device is held in its unlocking position but is free to be moved toward its locking position against the action of the spring.

100 6. In a pleasure railway, the combination with the car, of a movable safety device for locking the passengers in their seats, a locking bar slidable vertically and provided with a member having a cam face and a shoulder, the safety device including a pivoted arm provided with a cam which, when the bar has dropped into its lowest position and the safety device has been swung into its locking position, cooperates 115 with said member to hold said device in its locking position but which, when the bar is raised to a determinate height, engages said cam face in the movement of the safety device away from its locking position and thereby still further lifts the bar and moves under said shoulder, thereby preventing the bar from dropping into locking position until the safety device is returned to its locking position.

110 7. In a pleasure railway, the combination with the car, of a pair of vertically extending guide plates thereon, a locking bar slid- 120 able between said plates and provided with a member having a cam face and a shoulder, 125

- 5 a safety device for locking passengers in their seats including an arm pivoted on said plates and provided at its pivoted end with a cam adapted to coöperate with said member to hold the safety device in its locking position when said bar has dropped down and adapted, when the bar has moved up, to move under said shoulder in the movement of the safety device away from locking position.

10 8. In a pleasure railway, the combination with the car, of a safety device movable thereon for locking the passengers in their seats, and movable locking means adapted in one position to positively hold the safety device in its locking position and in its other position to releasably hold the safety device from moving from its unlocking position toward its locking position.

15 9. In a pleasure railway, the combination with the car, of a safety device movable thereon for locking the passengers in their seats, and a locking device adapted when in one position to positively retain the safety device in its locking position and adapted when in another position to releasably hold the safety device in its unlocking position, said locking device tending by gravity to move from the second position to the first.

20 10. In a pleasure railway, the combination with the car, of a safety device movable thereon for locking the passengers in their seats, and a locking device adapted when in one position to positively retain the safety device in its locking position and adapted when in another position to releasably hold the safety device in its unlocking position, said locking device tending by gravity to move from the second position to the first.

25 11. In a pleasure railway, the combination with the car, of a safety device movable thereon for locking the passengers in their seats, and locking means adapted when in one position to positively retain the safety device in its locking position and adapted when in another position to be itself positively retained in such position by the safety device when the latter is moved into unlocking position, said locking device including means adapted when the safety device is in unlocking position to releasably hold the safety device in its unlocking position.

30 12. In a pleasure railway, the combination with the car, of a safety device movable thereon for locking the passengers in their seats, and movable locking means adapted in one position to positively hold the safety device in its locking position and adapted when in another position to be moved into one extreme position, and adapted, when in the other extreme position, to lock the safety device from moving away from its locking position and thereby to be moved into a second position, and adapted, when in a third position, to lock the safety device from moving away from its locking position.

35 13. In a pleasure railway, the combination with the car, of a safety device movable thereon for locking the passengers in their seats, and a locking device adapted when in an intermediate position, to be actuated by the safety device in the latter's movement away from its locking position and thereby to be moved toward one extreme position, and adapted, when in the other extreme position, to lock the safety device from moving away from its locking position, and a cam arranged, in the travel of the car, to move said locking device from the last named position toward the second.

40 14. In a pleasure railway, the combination with the car, of a safety device movable thereon for locking the passengers in their seats, and a locking device adapted when in one position to positively retain the safety device in its locking position and adapted when in another position to be itself positively retained in such position by the safety device when the latter is moved into unlocking position, said locking device including means adapted when the safety device is in unloading position to releasably hold the safety device in its unlocking position, and a cam arranged, in the travel of the car, to move said locking device from the first position toward the second.

45 15. In a pleasure railway, the combination with the car, of a safety device movable thereon for locking passengers in their seats, a locking device adapted, when in an intermediate position, to be actuated by the safety device in the latter's movement away from its locking position and thereby to be moved toward one extreme position, and adapted, when in the other extreme position, to lock the safety device from moving away from its locking position, and a cam adapted, in the travel of the car, to move such locking device from the last named position to said intermediate position.

50 16. In a pleasure railway, the combination with the car, of a safety device movable thereon for locking passengers in their seats, a locking device adapted, when in an intermediate position, to be actuated by the safety device in the latter's movement away from its locking position and thereby to be moved toward one extreme position and in such position releasably hold the safety device in its unlocking position, and adapted, when in the other extreme position, to lock the safety device from moving away from its locking position, and a cam adapted, in the travel of the car, to move said locking device from its last named position to said intermediate position.

55 17. In a pleasure railway, the combination with the car, of a safety device movable thereon for locking passengers in their seats, a locking device adapted, when in an intermediate position, to be actuated by the safety device in the latter's movement away from its locking position, and a cam adapted, in the travel of the car, to actuate the locking means and move it from its positive-locking position toward its releasably-locking position.

its locking position and thereby to be moved toward one extreme position and in such position releasably hold the safety device in its unlocking position and be itself positively retained in such position by the safety device, and adapted, when in the other extreme position, to lock the safety device from moving away from its locking position, and a cam adapted, in the travel of the car, 10 to move said locking device from its last named position to said intermediate position.

18. In a pleasure railway, the combination with the car, of a safety device movable thereon for locking the passengers to their 15 seats, and a vertically extending locking bar slidable in the direction of its length and adapted to be upheld by the safety device when the latter is in locking position and to slide down by gravity, as the safety device 20 is moved into locking position, into position to lock the safety device from returning, and a cam adapted, in the travel of the car, to raise the slidable locking bar into position to allow the safety device to be returned 25 into unlocking position.

19. In a pleasure railway, the combination with the car, of a movable safety device for locking the passengers in their seats including a pivoted arm having a cam, and 30 a locking bar having a cam adapted, when the safety device is moved away from its locking position, to move in front of the cam on the arm and thereby lock the safety device from being returned to its unlocking 35 position, and a cam arranged, in the travel of the car, to move the locking bar to cause the cam carried thereby to recede from the cam on the arm and thereby permit the safety device to be returned to its unlock- 40 ing position.

20. In a pleasure railway, the combination with the car, of a movable safety device for locking the passengers in their seats including a pivoted arm, a locking bar slidable

vertically and provided with a member having a cam face and a shoulder, said arm having a cam adapted, when the locking bar is raised to a determinate height, to engage said cam face in the movement of the safety device away from its locking position and thereby still further lift the locking bar and move under said shoulder, thereby holding the locking bar up, and a cam arranged, in the travel of the car, to actuate the locking bar and raise it to said determinate height. 45 50 55

21. In a pleasure railway, the combination with the car, of a movable safety device for locking the passengers in their seats, a locking bar slidable vertically and provided with a member having a cam face and a shoulder, the safety device including a pivoted arm provided with a cam which, when the bar has dropped into its lowest position and the safety device has been swung into its locking position, coöperates with said member to hold said device in its locking position but which, when the bar is raised to a determinate height, engages said cam face in the movement of the safety device away from its locking position and thereby still further lifts the bar and moves under said shoulder, thereby preventing the bar from dropping into locking position until the safety device is returned to its locking position, and a cam, extending in the direction 60 65 70 75 of travel of the car, and adapted, in the travel of the car, to engage said bar and raise it to said determinate height and thus permit the safety device to move out of its locking position. 80

In testimony of which invention, I have hereunto set my hand, at New York, N. Y., on this 8 day of April, 1914.

LA MARCUS A. THOMPSON.
